UNITED STATES PATENT OFFICE.

JOHN HENRY CROSS, OF RED WING, MINNESOTA, ASSIGNOR TO THE WATERMAN-WATERBURY COMPANY, OF MINNEAPOLIS, MINNESOTA, A CORPORATION.

AGITATOR.

1,294,775.

Specification of Letters Patent. Patented Feb. 18, 1919.

Application filed May 2, 1918. Serial No. 232,113.

To all whom it may concern:

Be it known that I, JOHN H. CROSS, a citizen of the United States, resident of Red Wing, county of Goodhue, State of Minnesota, have invented certain new and useful Improvements in Agitators, of which the following is a specification.

My invention relates to an underground vault type of waterless closet and the object of the invention is to provide a device for agitating the liquid solution in the vault, breaking up the fecal matter and positively and quickly reducing the contents of the vault to a semi-liquid state.

A further object is to provide a device of the class described which is easily accessible through the top of the vault and is of such construction that it can be folded for insertion into the vault or removal therefrom.

The invention consists generally in various constructions and combinations, all as hereinafter described and particularly pointed out in the claims.

In the accompanying drawings forming part of this specification,

Figure 1 is a view of a waterless vault with the wall of the vault broken away to show the position of the macerator therein,

Fig. 2 is a sectional view through the macerator,

Fig. 3 is an end view of the same, with the middle portion broken away, showing the means for suspending the macerator in the top of the vault.

In the drawing 2 represents the floor of the toilet, 3 the toilet bowl having the usual cover 4 and vent 5. 6 is a pipe leading from the bowl to a vault 7 arranged preferably below the foundation wall 8 and having a manhole 9 and cover 10 on the surface outside the foundation wall. In this vault I place a suitable quantity of a chemical solution, and for the purpose of breaking up and disintegrating the matter in the solution I make use of the following described device which forms the subject matter of my invention.

This device, which I prefer to designate as a macerator, consists of a pair of base or lower bars 11 which are pivotally connected at 12 to a pair of upright bars 13 and a pair of inclined bars 14 connect the upper ends

of the bars 13 with the bars 11, thereby forming a triangular shaped frame. In the top of the vault is secured a strap 15 having depending ears 16 and bolts 17 pass through said ears and through the adjacent ends of the bars 13 and 14 and form pivotal supports for said bars on said ears and said bolts are held in place by suitable means, such as cotter pins 18. When these pins are removed, the bolts may be withdrawn and the bars detached from the ears to allow the frame to be folded or collapsed and removed from the vault through the manhole opening 9. The insertion of the frame into the vault may be accomplished in the same way.

At the lower ends of the bars 13 I provide a blade 19 having a series of openings 20 therein and knives 21 formed by pressing the metal out of the blade 19. These knives and openings are preferably, as shown in Fig. 3, approximately semi-circular in form, the knives being inclined slightly with respect to the vertical surface of the blade from which they are pressed. Said blade hangs vertically in the solution so that when the frame is oscillated, the blade drawn through the solution or semi-liquid will flow through the openings and the solid matter contacting with the knives will be broken up and disintegrated. At the lower ends of the bars 14 I provide a similar blade 19^a having openings 20^a therein formed by pressing out knives 21^a. This blade is inclined, forming substantially a continuation of the bars 14 and the knives 21^a act as beaters to break up the solids in the solution and thoroughly disintegrate the matter 90 therein.

A strap 22 is secured to the blade 19^a and has upwardly turned ends 23 for attaching a rod 24 thereto which extends up through the pipe 6 and to a point near the closet seat and is provided with a finger grip 25 by means of which the macerator may be lifted and oscillated in the vault to thoroughly agitate and break up the contents. The purpose of this agitation is to allow the chemical agent to have access to all parts of the matter therein and quickly and efficiently deodorize and disinfect it. The blades or wings are so shaped that a whirlpool effect will be produced in the solution. The forward blade of the macerator is located

directly under the bowl and at a suitable angle to have immediate action on the fecal matter falling into the vault and the downward flail-like action of the blade operating in conjunction with the knives will quickly reduce the contents of the vault to a semi-liquid state.

The knives are preferably set at an angle of about 45 degrees to the blades and their main function is to reduce the toilet paper to a pulp-like condition and break up and disintegrate any solids in the solution. The blades are so constructed and their relative position is such that the stroke necessary for the proper reduction of the solids need not exceed an eight inch maximum. Two points of connection for the rod with the macerator are shown, one near the lower end of the forward blade and the other in the rear of it. This allows the closet bowl to be turned at any angle to the vault and still allow the operating rod to be practically vertical. The number of openings in the blades and their size and shape are not of particular importance and may be varied to suit different conditions, the particular features of the device being the manner of mounting it in the vault, the position of the blades and their line of travel.

I claim as my invention:

1. The combination, with a closet vault adapted to contain a chemical solution, of an agitator suspended therein and comprising an oscillating frame and agitating blades carried thereby, and means for oscillating said frame.

2. The combination, with a closet vault adapted to contain a chemical solution, of an agitator suspended therein and comprising a frame, a rear blade vertically arranged in said agitator, a forward blade mounted at an incline therein, said blades having openings therein and means for oscillating said frame.

3. The combination, with a closet vault adapted to contain a chemical solution, of an agitator arranged therein and comprising a frame, blades mounted in angular relation in said frame and having openings therein, and means for moving said frame back and forth through said chemical solution.

4. The combination, with a closet vault adapted to contain a chemical solution, of an agitator arranged therein and comprising a frame, blades mounted in angular relation in said frame and having openings therein

and knives formed on said blades and means for moving said frame back and forth through said solution.

5. The combination, with a closet vault adapted to contain a chemical solution and having a man hole and cover therefor, of an agitator comprising a folding frame pivotally supported in the top of said vault adjacent said opening and having removable pivot pins accessible through said opening and means for oscillating said agitator in said solution.

6. The combination, with a closet vault adapted to contain a chemical solution, of a triangular frame pivotally supported in the top of said vault to oscillate therein, a rear blade mounted on the lower portion of said frame and having openings therein and knives adjacent said openings, a forward blade mounted at an angle to said first named blade and also having openings therein and knives adjacent said openings, and means extending upwardly through the top of said vault for moving said frame back and forth through said solution.

7. The combination with a closet vault adapted to contain a chemical solution and having a manhole and a cover therefor, of a folding frame having means for supporting it in the top of said vault for oscillation therein said means being located near said manhole for convenience of insertion or removal of said frame therethrough.

8. The combination, with a closet vault adapted to contain a chemical solution, of an agitator suspended in the top of the vault and depending therein and comprising an oscillating frame having means for agitating and disintegrating the solids in the closet vault, and means for operating said frame.

9. The combination, with a closet vault adapted to contain a chemical solution, of an agitator suspended in the top of the vault and depending therein and having freedom of movement forward and backward through said solution, said agitator being provided with means for separating and disintegrating the solids in said solution, and means for operating said agitator.

In witness whereof I have hereunto set my hand this 22nd day of April, 1918.

JOHN HENRY CROSS.
